GAME APPARATUS

Archie Bechtol, Chicago, Ill.

Application February 15, 1934, Serial No. 711,375

4 Claims. (Cl. 273—121)

This invention relates to game apparatus. It is an object of this invention to provide an improved game apparatus which is relatively simple and inexpensive in construction and efficient in use.

Another object of the invention is to provide a game apparatus comprising the combination of a member providing a ball playing surface provided with ball-receiving scoring elements or pockets; a ramp for conducting the balls onto the playing surface toward one end thereof; means for projecting the balls one at a time along the ramp onto the playing surface; resilient rails or cushions defining marginal edges of said playing surface; a ball-deflecting member arranged in the path of travel of the balls from the ramp onto the playing surface; and means for positioning the said ball-deflecting member in any preselected one of various positions so as to deflect the balls one at a time at various preselected points on said cushions so as to carom the balls from the latter into preselected ones of said ball-receiving elements or pockets.

An additional object of the invention is to provide an amusement game apparatus requiring much of the knowledge of angles required in playing billiards.

Other objects will appear hereinafter.

The invention consists in the novel combination and arrangement of parts to be hereinafter described and claimed.

The invention will be best understood by reference to the accompanying drawings, showing the preferred form of construction and in which:

Fig. 1 is a top plan view of a game apparatus embodying a preferred form of the invention;

Fig. 2 is a longitudinal, vertical sectional view of the structure shown in Fig. 1;

Fig. 3 is a perspective detail view, partly in section, illustrating a preferred form of the ball-deflecting member and means for adjustably positioning the same;

Fig. 4 is a sectional detail view on line 4—4 in Fig. 3;

Fig. 5 is a sectional detail view on line 5—5 in Fig. 2;

Fig. 6 is a sectional detail view on line 6—6 in Fig. 1 showing one of the ball-receiving elements or pockets; and

Fig. 7 is a sectional detail view showing another form of ball-receiving element or pocket.

A preferred form of the new game apparatus is illustrated in the drawings, being generally indicated therein at 10, and comprises a cabinet 11 which includes a member 12 providing an in-

clined ball playing surface 13. This member 12 is provided with ball exit scoring openings 37. Leading onto the playing surface 13, toward one end thereof, is a ramp 14, and arranged at the lower end of the ramp for propelling balls one at a time therealong up onto the playing surface 13 is a ball-projecting device 15.

Arranged in the path of travel of the balls as they travel from the ramp 14 onto the playing surface 13 is a ball-deflecting member 28, which is pivotally mounted above the playing surface 13 upon a vertical supporting post 16 (Fig. 3) for movement over the underlying portion of the playing surface 13. This ball deflector 28 is preferably made in the form of a block of rubber or other resilient material.

Attached to the supporting post 16 (Fig. 3) at the lower end of the latter and below the inclined member 12 which provides the playing surface 13, is a link 17 and pivotally connected to this link 17, as at 18, is one end of a relatively long horizontal bar 19 (Fig. 3) which extends below the playing surface 13 (Fig. 2) toward the lower end of the latter.

Attached to that end of the bar 19 that is opposite the end attached to the link 17 is a follower 20 which is threaded into a horizontal operating screw 21. This follower 20 is prevented from turning and is guided in its movement by a guide rod 38. This operating screw has an unthreaded end portion 24 that is rotatably mounted in a bearing sleeve 22 (Fig. 4). This bearing sleeve 22 is mounted in a vertical end wall 23, of the cabinet 11, which is arranged at the lower end of the playing surface 13.

Rotatably mounted upon the unthreaded end portion 24 of the operating screw 21 is a flanged extension 25 of a disc 26 which is arranged exteriorly of the cabinet 11, adjacent the wall 23 thereof, and below the ball projecting device 15. This disc 26 carries an operating handle 27.

The flanged disc 26 has a pressure release or so-called slip connection with the unthreaded end portion 24 of the operating screw 21. This slip connection comprises an annular row of cup-shaped sockets or indentations 29 formed in the screw portion 24. These sockets 29 are adapted for selective latching engagement with a ball 30 that is arranged, with its urging spring 32, in a groove 31 that is formed in the flanged extension 25 of the disc 26.

The engagement of the ball 30 in any one of the sockets 29, under the action of the spring 32, is sufficient to latch the sleeve 25 to the screw portion 24 so that the operating screw 21 may be 55

rotated by turning the handle 27 and disc 26, so as to cause the follower 20 to move axially along the screw 21. This movement of the follower 20 axially along the screw 21 causes the operating 5 bar 19, link 17, and post 16 to move in correspondence therewith so that the ball deflector 28 may be adjusted or pivoted into any preselected one of various positions within its allowed range of movement upon the playing surface 13.

10 By so adjusting the ball deflector 28 the played balls may be projected up the ramp 14 by the ball projecting device 15 and engaged with the ball deflector 28 so as to be deflected thereby toward any preselected point on the relatively 15 long resilient side rail or cushion 33 which defines one marginal edge of the playing surface 13; whereupon the played ball may gravitate down the playing surface 13 and drop through one of the ball exit scoring openings 37 formed 20 in the member 12 for return to the ball projecting device 15 (by suitable means, not shown); or, the played ball may, depending upon the player's judgment of angles and skill in manipulating the deflector 28, be deflected from the rail or 25 cushion 33 toward one of the shorter but similar rails 34, 35 and 36. These rails 33, 34, 35 and 36 are preferably made of rubber or analogous resilient material, after the manner of the side rails or cushions of billiard tables and are placed 30 at angles relative to each other so that after the played ball engages the deflector 28 and is deflected thereby against the long rail 33 it will rebound or carom from the latter toward one or more of the side rails 34, 35 and 36 and, depending upon the skill of the player, be directed 35 either into one of a series of ball-receiving pockets 39 (Fig. 6) arranged at intervals upon the playing surface 13 or into one of another group of ball-receiving elements or scoring pockets 40 40 which are arranged in a row at the upper end of the playing surface 13 (Figs. 1, 3 and 7).

By an examination of Figs. 1 and 6, and Figs. 3 and 7, it will be ascertained that the inlets or mouths 41 and 42 of the scoring pockets 39 and 45 40, respectively, open out upon the playing surface 13 toward the lower end of the latter so that in order to score a played ball into one of these pockets 39 or 40 the player must skillfully manipulate the ball deflector 28, with a proper 50 understanding of angle play, that is familiar to all billiard players, so that the ball will be deflected by the member 28 toward the long rail or cushion 33 and thence rebound from the latter against one or more of the rails 34, 35 and 36 from 55 which, in turn, the played ball may rebound up the inclined playing surface 13 into a preselected one of the scoring pockets 39 or 40; it being noted that the played balls can not be directly guided by the deflector 28 into any of the pockets 60 65 39 or 40 but must be directed into these pockets from the cushions or rails 33, 34, 35 and 36 by a skillful manipulation of the deflector 28 and a knowledge of the angle play involved in order to accomplish this end. For these reasons play upon the new game apparatus resembles, in many respects, the game of billiards.

Each of the scoring pockets 39 comprises an upright housing 43. These housings 43 are attached to the member 12 and open at their lower 70 ends, as at 44 (Fig. 6) through the member 12 so as to discharge the balls therefrom below the playing surface for return to the ball-projecting device 15 (by means not shown). A resilient bumper 45 of rubber or analogous material surrounds each of the housings 43 except at the

inlets or mouths 41 of the same so as to deflect the balls striking the housings at points other than at the inlets 41 thereof.

The scoring pockets 40 are formed by an angled row of U-shaped frames 46 which are attached 5 to an upright wall 47 arranged at the upper end of the playing surface 13. The parallel side walls 48 of these frames 46 are spaced by members 49 which define the inlets 42 to the pockets 40. These members 49 may well be made of resilient 10 material such, for example, as rubber or the like, or other suitable material so as to deflect the balls away from the inlets thereto and make it more difficult to score the balls in the pockets 40.

After entering the pockets 40 the balls fall 15 therefrom through exit openings 50 formed in the member 12, one at the bottom of each pocket 40, for return to the ball projecting device or plunger 15 (by means not shown).

If the player attempts to force the deflector 28 20 beyond the limit of its travel or operates the disc 26 and its handle 27 violently, the consequent rotation of the operating screw portion 24 will force the latch ball 30 out of its socket 29 against the action of the spring 32 and thereby operatively 25 disconnects the sleeve 25 and operating screw 24-21 and thus prevents rotation of the operating screw 21 and movement of the follower 20, operating bar 19, and ball deflector 28.

The cushions or rails 34-35 may be spaced 30 at their lower ends, if desired, as at 51 (Fig. 1) so as to provide access for the balls to a free play opening 52.

While I have illustrated and described the preferred form of construction for carrying my invention into effect, this is capable of variation and modification, without departing from the spirit of the invention. I, therefore, do not wish to be limited to the precised details of construction set forth, but desire to avail myself of such variations and modifications as come within the scope of the appended claims.

Having thus described my invention what I claim as new and desire to protect by Letters 45 Patent is:

1. In a game apparatus: a cabinet including a member providing an inclined playing surface and said member having ball exit scoring openings therein; a ramp extending along one marginal edge of said playing surface; means for propelling balls one at a time through said ramp onto the upper portion of said playing surface so that they may gravitate thereover and enter into said exit openings; a ball-deflecting member 50 movably mounted upon said playing surface in the path of balls emerging from said ramp; and means for positioning said ball-deflecting member at different times in various positions so as to deflect balls therefrom at preselected ones of 55 said exit openings; said second-named means including a member adjustably mounted in a wall of said cabinet and having a handle portion disposed exteriorly thereof; said second-named means including a member slidably mounted in 60 said cabinet below the said playing surface; said slidable member having an operative connection at one end with said ball-deflecting member and having an operative connection at its other end with said adjustable member.

2. In a game apparatus: a cabinet including a member providing an inclined playing surface and said member having ball exit scoring openings therein; a ramp extending along one marginal edge of said playing surface; means for 70

- propelling balls one at a time through said ramp onto the upper portion of said playing surface so that they may gravitate thereover and enter into said exit openings; a ball-deflecting member 5 movably mounted upon said playing surface in the path of balls emerging from said ramp; means for positioning said ball-deflecting member at different times in various positions so as to deflect balls therefrom at preselected ones of 10 said exit openings; said second-named means including a screw member adjustably mounted in a wall of said cabinet and having a handle portion disposed exteriorly thereof; said second-named means including a follower mounted for 15 movement axially along said screw member; and a member slidably mounted in said cabinet having an operative connection at one end with said ball-deflecting member and having an operative connection at its other end with said follower. 20
3. In a game apparatus: a cabinet including a member providing an inclined playing surface; a ramp extending along one marginal edge of said playing surface; means for propelling balls one at a time along said ramp onto the upper portion 25 of said playing surface so that they may gravitate thereover; a ball deflecting member arranged upon the upper portion of said playing surface in the path of balls emerging from said ramp; and means for moving said ball-deflecting member at different times into various preselected positions; said second-named means 30 comprising a screw member adjustably mounted in a wall of said cabinet and having a handle portion projecting exteriorly thereof adjacent the lower end of said playing surface; a follower mounted for axial movement along said screw member; and a slidable member movably mounted in said cabinet below said playing surface; said slidable member having an operative connection at one end with said follower and having an operative connection at its other end with said ball-deflecting member. 5
4. In a game apparatus, a cabinet including a member providing an inclined playing surface; a runway extending along one marginal edge of said playing surface; means for propelling balls 15 one at a time along said runway onto the upper portion of said playing surface so that they may gravitate thereover; a ball deflecting member arranged upon the upper portion of said playing surface in the path of balls emerging from said runway; means for moving said ball deflecting member into various preselected positions; said means comprising a member adjustably mounted in a wall of said cabinet below the playing surface and having a handle portion projecting exteriorly of the cabinet adjacent the lower end of the playing surface; and means in said cabinet below the playing surface and operatively connecting said ball deflecting member with said adjustable member. 20 25

ARCHIE BECHTOL.
